ENVELOPE FASTENER

John W. Fitzgerald, Boston, Mass., assignor to
 Ames Safety Envelope Company, Boston, Mass.,
 a corporation of Massachusetts

Application February 12, 1930, Serial No. 427,812

1 Claim. (Cl. 229—78)

This invention relates to envelope fasteners and it proposes a simple and practical construction which while holding the envelope closed with complete security, acts as a tell-tale in response to 5 tampering with the envelope, by breaking at an unexpected point in such manner as to leave the parts thereof irreparably separated.

The principal object of the invention is the provision of a fastener, particularly of the stud and eyelet type in which the metal of the stud at some portion intermediate the top of the shank and the securing element of the stud is ruptured or otherwise weakened in the manufacture of the stud in such manner that the shank of the stud will break 15 off under the strain attending the insertion of a knife or other instrument between the stud and eyelet in the effort to unfasten these parts.

Other objects of the invention will appear as the following description of a preferred and practical embodiment thereof proceeds.

In the drawing in which the same characters of reference are used throughout the several figures to denote identical parts:

Figure 1 is a plan view of the flap and of an envelope illustrating the base portion of the stud;

Figure 2 is an underneath plan view of the same and of the envelope, the material of the envelope being broken away so as to disclose the top of the stud and the eyelet;

Figure 3 is an exploded view in perspective showing the stud and eyelet;

Figure 4 is a section taken along the line 4—4 of Figure 1;

Figure 5 is a section taken along the same line 35 of the same figure, but showing the parts in broken relation;

Figure 6 is a plan view on an enlarged scale of the base of the stud; and

Figure 7 is a plan view taken along the line 40 7—7 of Figure 5.

Referring now in detail to the several figures, the stud in general is indicated by the numeral 1, 2 representing in general the structure of the eyelet. The stud comprises a base portion 3 preferably formed with pointed lugs 4 by means of which it may be secured to the flap of an envelope in the manner illustrated in Figure 1, by bending the lugs at right angles to the material of the envelope, piercing the envelope with the down-turned lugs and turning the lugs over on the inside of the envelope in the manner indicated in Figure 5, the material of the envelope being frictionally held beneath the inwardly turned lugs. Such means of securing a stud to an envelope is, 55 of course, old and in the present instance, the

shank 5 of the stud is directed inwardly between the flap and the adjacent side of the envelope.

The eyelet 2 is secured in a manner similar to that of the stud at the adjacent side of the envelope and in alignment with the stud, said eyelet being provided with lugs 6 similar to the lugs 4 on the stud. Said eyelet may be of any preferred construction, but as here shown, by way of example, the eyelet comprises a base portion 7 stamped to form a channel 8 thereby defining a boss 9 in the form of an inverted cup. Said boss being formed at its center with an aperture 10 somewhat smaller than the head 11 of the shank of the stud.

In order that the shank of the stud shall pass through the aperture 10, the walls defining said aperture are made yielding or resilient, and radial slots 12 are formed in said walls, opening into said aperture defining leaves 13 which are forced aside when the shank is forced through said aperture, said leaves through their resiliency, spring back toward their original position after the head of the shank has passed through said aperture so as to closely and frictionally engage said shank.

The face of the aperture 10 is so related to the diameter of the shank that when the latter is in place in said aperture, the leaves 13 cannot quite re-assume their original positions so that if it is attempted to unfasten the device by separating the stud from the eyelet, said leaves exert a toggle action against the sides of said shank or against the slight over-hang 14 which defines the head of said shank rendering the separation of these parts quite difficult, and only capable of being accomplished when some instrument is forced into the slots 12 and the parts violently pried. It is sometimes attempted to tamper with sealed mail in this manner, and, in the absence of the provision of the present invention, if the prying action is successful, it is quite possible to restore the parts to their original state with a little manipulation and then to close the fastening device in the normal manner so that it becomes difficult or quite impossible to detect that the mail has been tampered with.

The present invention provides an inevitable tell-tale with respect to such tampering, inasmuch as the material from which the stud is made is weakened at some point between the lugs 4 by which the stud is secured to the envelope and the top 11 of the shank so that it will break apart at this point under a strain considerably less than any stress that can be 110

applied before the stud and eyelet may be separated at their point of juncture.

Figure 3 shows that the stud has been weakened adjacent the base of the shank as indicated at 15, the metal having been ruptured or partly broken through along a circular line surrounding the shank of said stud. The weakened portion of the metal is clearly shown on a larger scale in Figure 4. The result of this weakening is that when the prying pressure is applied between the stud and eyelet, the shank of the stud will suddenly break away as indicated in Figure 5, leaving the shank and the eyelet inseparably united and leaving the shank and the base of the stud broken apart in such a manner that they cannot be united.

This form of tell-tale is particularly effective, since the weakened portion is perfectly inobvious to anyone upon casual inspection and from the fact that the parts when once broken away cannot be united.

A device of this character is particularly advantageous from the standpoint of manufacture, since no more metal is required than in manufacturing the ordinary forms of fastener in which this tell-tale feature is absent and no variation in the steps of manufacture is required except the one simple step of bringing a die down upon the base of the stud adjacent the shank for weak-

30

ening the metal to the desired degree. While the stud is weakened to the extent that it will surely break off before sufficient pressure is applied between the stud and eyelet to separate these parts at their ordinary place of juncture, yet the tenacity of the metal along the weakened portion is amply sufficient to maintain the stud intact through the ordinary exigencies of use.

80

It is to be understood that while I have for purpose of illustration shown a particular form of stud and eyelet, yet the specific construction of either of these parts is altogether immaterial to the inventive concept which concerns itself solely with the weakening of one of the integral parts of the fastener in such a way that the said integral part will break in two at the place of weakening, thus perpetuating the opened condition of the envelope and giving evidence of the fact that it has been tampered with.

85

What I desire to claim as my invention is:

90

In an envelope fastener, a stud member comprising a plate with fastening means thereon and a shank provided with an inwardly facing shoulder, there being a weakened breaking portion between said means and said shoulder, in combination with an eye member having a snap irremovably engaging said shoulder.
